UNITED STATES PATENT OFFICE.

HENRI SCHNEIDER, OF PARIS, FRANCE.

BREECH-LOADING ORDNANCE.

SPECIFICATION forming part of Letters Patent No. 449,385, dated March 31, 1891.

Application filed June 17, 1890. Serial No. 355,796. (No model.)

To all whom it may concern:

Be it known that I, HENRI SCHNEIDER, a citizen of the Republic of France, and a resident of Paris, France, have invented Im-
5 provements in Breech-Loading Ordnance, of which the following is a specification.

This invention has for its object improvements in the construction of the breech-loading mechanism of ordnance, and the improvements relating to the closing of the breech of guns of medium and large calibers, as hereinafter explained, are designed to obtain as rapid a fire as possible by facilitating the operation of loading and reducing the number
10 of operations required. These numerous operations ordinarily comprise the following, namely: first, opening the breech; second, placing the planchette or charging-plate in position; third, introducing the projectile; fourth, introducing the charge; fifth, closing the breech; sixth, extracting the exploded primer; seventh, introducing a fresh primer in its place; eighth, cocking the hammer when a percus-
15 sion-primer is employed, or making the connections of the wires when the gun is fired by electricity. In ordinary quick-firing guns a case is employed which contains the charge and the projectile; but the empty case has to be extracted after each shot. This arrangement, though advantageous for guns of small caliber, ceases to be advantageous with guns of medium caliber, and becomes altogether impracticable with guns of a certain size, owing to the weight of the complete charge
20 and the excessive length of the cases. It is, moreover, impossible to employ the brown prismatic powders with advantage, owing to the cylindrical or taper form of the cases, and at the same time the well-known advantages
25 of the form of the breech-chamber are lost. With the improved arrangement according to this invention all the ordinary manipulations connected with the primers, the firing, the charging-plate, or the extraction of the cases
30 are dispensed with by combining the movements of these parts with those of opening and closing the breech, as hereinafter explained.

In order that my said invention may be
35 fully understood, I shall now proceed more particularly to describe the same, and for that purpose shall refer to the several figures on

the annexed sheet of drawings, the same letters of reference indicating corresponding parts in all the figures.

55

Figure 1 of the accompanying drawings illustrates in vertical and longitudinal section on line 5 6 of Fig. 2 a breech for a gun of large caliber according to this invention. Fig. 2 is a front view of the breech as it appears im-
60 mediately after firing. Fig. 3 is likewise a front view of the breech as it appears at the moment when, after being rotated through one-sixth of a revolution, the breech-screw is about to be drawn back. Fig. 4 represents 65 the bracket and support of the hinge. Fig. 5 represents a horizontal section on the line 1 2, Fig. 3. Fig. 6 represents in longitudinal section the loading-plate. Fig. 7 represents a front view of the said plate. Fig. 8 repre-
70 7c sents a detail in section on the line 3 4, Fig. 7.

The breech-screw or obturator is constructed with interrupted screw-threads divided into three equal parts, and is preferably provided with a special plastic gas-check, such as 75 Schneider's composite gas-check. The screw disconnected from the gun-barrel is carried by a bronze or metal bracket, the connection between the bracket and screw being obtained with the aid of a double catch, as in the breech-
80 closing mechanism employed in the French navy. The head of the lever-handle employed for working the screw is provided with a cam 85 engaging with a recess in the rear face of the barrel, so as to prevent accidental displacement. The employment of the composite obturator and the perfect adjustment of the parts insure great speed in the movements of opening and closing the breech. The mechanism for automatically changing or renew-
90 ing the primers is contained in the back face of the breech-screw, and consists of a disk or barrel A, Figs. 1, 2, and 5, carrying the primers and operated automatically by a lever B. The disk A, the dimensions of which are 95 regulated according to the size of the breech-
screw, is arranged to contain the greatest possible number of electric fuses or primers e, which are screwed into the disk in a circle, so that as the disk rotates on its axis a the primers e are successively placed opposite the vent x. A forked lever B oscillates on an axis c, and communicates a rectilinear motion from front to rear and, vice versa, to the disk. With
100

this object the extremities of the fork are provided with pins *b*, engaging with a circular groove *a'* in the boss or pivot *a* of the disk *A*. The other extremity or tail of this lever 5 is of suitable form for working in a helical or inclined groove *d* in the support of the hinge *D*, Figs. 1, 2, 4, and 5. A piston *E*, Figs. 1 and 5, acted on by a spring *F*, presses against a flat surface *m n*, or on the corners or angles 10 at *m* and *n* on the lever *B* when the latter oscillates on its fulcrum. The disk *A* is provided on its periphery with as many teeth and notches as there are primers. A locking-bolt *G*, Figs. 2 and 3, acted on by a suitable 15 spring, engages with these notches in succession and prevents the disk from rotating freely on its center or becoming accidentally displaced. The bracket or support of the breech, Figs. 2, 3, and 4, is provided with a 20 pawl or finger *L*, capable of rotating or oscillating on a pin *l*, but retained in a certain position by the action of a blade-spring *H* and a stop *h*.

In order to facilitate the introduction of the 25 projectile into the gun and to prevent injury to the threads of the screw, an angular charging plate or planchette *K*, Figs. 6 and 7, of bronze or other suitable metal is provided in the breech-opening. The upper part of this 30 plate being slightly curved forms a cradle for the reception of the projectile, and is contained in a cavity *k* in the breech-opening at the time of closing the breech, so as not to interfere with the movements of rotation and 35 displacement of the screw. The vertical part *M* of this angular plate or carrier slides vertically in a groove *g*, cut in the face of the breech. Another groove cut at right angles to the first acts as guide and support to a bar *N*, provided 40 with an incline *i* and rack-teeth *C*. An incline *o* on the plate *K* slides on the incline *i* and the rack *C*, gearing with a toothed quadrant *R*, fixed on the pin *S* of the hinge, which moves with the bracket or support of the 45 breech-screw.

The action of the improved mechanism is as follows: After firing, the plate *A* and its lever *B* occupy the position represented in Figs. 1 and 2, the plate *K* being underneath the screw, 50 as indicated in Figs. 6 and 7. By turning the hand-lever to the left to the extent of one-sixth of a revolution, after suitably raising it, the screw-threads on the breech-block are disengaged from the threads in the breech-opening 55 at the same time the lever *B*, one end of which slides in the helical groove *d*, oscillates, and drawing back the disk *A* disengages the exploded primer *e* from the vent *x*. During the rotation of the screw all these parts are 60 moved together. One of the teeth on the disk *A* comes in contact with the finger *L*, Fig. 3, and as the rotary motion continues the disk is caused to turn upon its axis to the extent of one division and presents a fresh 65 primer in front of the vent. When the sixth of a revolution is completed, the bolt *G* locks

the disk *A* and prevents it from becoming accidentally displaced, and the piston *E* presses on the flat part *m n* of the lever *B*, Fig. 5. All the parts then become stationary and remain 70 so during the other movements connected with the opening and closing of the breech. At the moment when the screw, being completely disengaged from the breech, actuates the bracket by causing it to rotate upon its 75 hinge, the toothed quadrant *R*, partaking of the same movement, actuates the rack *C*, which by means of inclines *i* and *o* raises the plate *K* slightly above the level of the adjacent screw-threads in the breech-opening. 80 The charge being now introduced, the breech is closed by similar movements in the reverse direction. During the rotation of the bracket and of the quadrant *R* the rack *C* and plate *K* return to their original positions and clear 85 the way for the introduction of the breech-screw. In rotating this screw for the purpose of re-engaging the screw-threads the lever *B*, the tail of which engages with the helical slot *d*, is caused to vibrate and move 90 forward the disk *A*, so as to insert a fresh primer into the vent *x*. These operations being completed, the loaded gun is ready for firing, the electrical connections being established automatically by the act of closing the 95 breech by the aid of an arrangement illustrated in Figs. 1 and 2, according to which a blade-spring, with two arms *r* and *t*, is employed, being suitably insulated on an ebonite block *s* to connect the extremity *y* of a 100 carefully-insulated conductor or wire with the center of the primer. On the other hand, a fine platinum wire in the interior of the primer connects the central portion with the outer part. The circuit can now be closed 105 through the metal of the gun and the primer. An interrupter or commutator interposed in the circuit is placed under the control of the gunner, who closes the circuit at the proper moment. On the passage of the current the 110 platinum wire in the primer becomes heated and burns, setting fire to the powder around it. As many shots can thus be fired in rapid succession as there are primers in the disk. A 115 without further attention being paid to the ignition, and when one disk is exhausted a fresh disk charged with primers can be substituted in place of the first. This exchange can be effected with great rapidity by simply causing the lever *B* to describe a complete oscillation, so as to disengage the boss or pivot *a* from the fork, thus enabling the exhausted disk to be removed and the charged disk 120 to be inserted in its place, the gun being then fired, as before, with the fresh series of 125 primers.

The magazine carrying the primers and the loading-plate *K* acting automatically, as hereinbefore described, enable guns of any caliber to be worked as quick-firing guns. 130

The forms and dimensions and the materials employed in the construction of the

parts constituting the improvements according to this invention can evidently be modified without departing from the principles of the invention.

5 Having now particularly described and ascertained the nature of my said invention and in what manner the same is to be performed, I declare that what I claim is—

1. In breech-loading guns, the combination 10 of the breech-screw with a removable disk pivoted in the breech-screw, the said disk provided with a series of primers, and means for automatically rotating the disk, substantially as and for the purpose set forth.

15 2. In breech-loading guns, the combination of a rotary toothed disk carried by the breech-screw and provided with a series of primers, with a breech-screw support provided with a spring-pawl to engage the teeth on the disk, 20 as and for the purpose set forth.

25 3. The combination of a breech-loading gun with a breech-screw and a disk provided with a series of primers, means controlled by the breech-screw for automatically rotating the disk, and means for moving it longitudinally 50 in the breech-screw as the latter is rotated, substantially as set forth.

4. In breech-loading guns, the combination 30 of a breech-screw, a rotating disk provided with a series of primers, with an oscillating lever engaging the disk, and means for automatically oscillating the lever from the breech-

screw as the latter is rotated, as and for the purpose set forth.

5. In breech-loading guns, the combination 35 of a rotating disk provided with a series of primers and a breech-screw support provided with a helical groove, with a lever, one end of which engages the disk, and the other end is adapted to slide in the helical groove, as and 40 for the purposes set forth.

6. In a breech-loading ordnance, the combination of a pivoted breech-screw support with a charging-plate in the breech, and means for automatically raising and lowering 45 the plate by the said support as the latter is turned, substantially as and for the purpose set forth.

7. In breech-loading ordnance, the combination of a pivoted breech-screw support, with 50 a charging-plate in a cavity of the breech, the said plate provided with an incline, a rack-bar having an incline engaging the incline on the charging-plate, and a toothed quadrant fixed on the pivot of the breech-screw 55 support and engaging the teeth of the rack, substantially as and for the purpose set forth.

In testimony whereof I have signed my name to this specification in the presence of two subscribing witnesses.

HENRI SCHNEIDER.
